UNITED STATES PATENT OFFICE

159,283

MUSICAL TOY

Moses Sivitz, Cincinnati, Ohio, assignor to
Bromo-Mint Company, Cincinnati, Ohio, a corporation of Ohio

Application April 22, 1949, Serial No. 2,203

Term of patent 14 years

(Cl. D34—15)

To all whom it may concern:

Be it known that I, Moses Sivitz, a citizen of the United States, residing at Cincinnati, in the county of Hamilton and State of Ohio, have invented a new, original, and ornamental Design for a Musical Toy, of which the following is a specification, reference being had to the accompanying drawing, forming a part thereof.

I claim:

The ornamental design for a musical toy, substantially as shown.

MOSES SIVITZ.
